UNITED STATES PATENT OFFICE.

CECIL L. WILSON, OF PORTLAND, OREGON.

GRAVE MARKER.

Application filed February 1, 1924. Serial No. 690,059.

To all whom it may concern:

Be it known that I, CECIL L. WILSON, a citizen of the United States, residing at Portland, in the county of Multnomah and State of Oregon, have invented new and useful Improvements in Grave Markers, of which the following is a specification.

The general object of my said invention is the provision of a grave marker of economical construction, adapted to withstand exposure to weather, and of such character that it may be expeditiously and easily and cheaply provided with lasting means for designating the person buried and for imprinting data regarding said party.

Another object of the invention is the provision of a grave marker adapted to strongly and securely hold a flag.

Other objects and practical advantages of the invention will be fully understood from the following description and claims when the same are read in connection with the drawings, accompanying and forming part this specification, in which:

25 Figure 1 is a front of the grave marker constituting the preferred embodiment of my invention.

Figure 2 is a vertical central section taken in the plane indicated by the line 2—2 of 30 Figure 1, looking toward the right.

Figure 3 is an elevation of the left hand edge of the marker.

Figure 4 is a rear elevation of the marker.

Figure 5 is a fragmentary vertical section taken in the plane indicated by the line 5—5 of Figure 2, looking toward the left.

Figure 6 is a fragmentary vertical section on the line 6—6 of Figure 4.

Figure 7 is a plan view of the blank from which is formed the crown member of the marker.

Figure 8 is a perspective of the top brace of the marker.

Figure 9 is a horizontal section taken in the plane indicated by the line 9—9 of Figure 4, looking downwardly.

Figure 10 is a view of one of the blanks from which the upright side members of the marker are formed.

Figure 11 is a plan view of the blank from which the front data carrying frame of the marker is formed.

Figure 12 is a front elevation of one of the letters used in conjunction with the crown member.

Figure 13 is a detail section taken at right

angles to Figure 12, and showing the letter in association with a portion of the crown member.

Figure 14 comprises view of a punctuation member adapted to be used in the crown member.

Figure 15 comprises disconnected views of spacing members adapted to be used in the crown member.

Figure 16 is an enlarged detail view of the closure means employed in the crown member.

Figure 17 is a vertical section taken in the plane indicated by the line 17—17 of Figure 16, looking toward the right.

Figures 18 and 19 are views showing the closure means for use on the data carrying frame, Figure 19 being taken on the line 19—19 of Figure 18.

Figure 20 is a front elevation of a plurality of letters for use in the data carrying frame.

Figure 21 is a front elevation showing the said letters in a single unit.

Similar numerals of reference designate corresponding parts in all of the views of the drawings.

My novel grave marker is formed of galvanized metal or other metal calculated to withstand exposure to the weather.

Among other elements the marker comprises upright side members 1 in parallelism. Each of the said members 1 is of angular form in cross-section, Figure 9, and is formed from a blank such as shown in Figure 10, and it will be noticed that each member 1 is provided with a projection 2, designed for use immediately under the angle brace hereinafter described. Each member 1 is sharpened as indicated by 3 to enable it to readily penetrate the ground. At 4 each of the members 1 is provided with apertures as illustrated.

In addition to the upright side members 1, the marker comprises a face plate 5, riveted at 6 to the side members 1, a horizontal angle brace 7 interposed between portions of the side members 1 and riveted at 8 to the side members 1 and the face plate 5, a top brace 9 with an aperture 10, a crown member 11 with an aperture 12 in registration with the aperture 10, and a plate 13, arranged slightly above the angle brace 7 and provided with an aperture 14, and riveted at 15 to the face plate 5. The several apertures 10, 12 and 14, alluded to are registered, and from

this it follows that the staff of a flag may be socketed in said apertures and rested in the horizontal portion of the cross brace 7. An apertured steel spring strip 15 is connected to and disposed below the plate 13 and is adapted to engage the staff of a flag so as to prevent casual displacement of the staff and flag when the bunting of the flag is subjected to the action of wind. In this 10 way a flag is securely held in the marker without liability of displacement, and this without interfering with the convenient placing and removal of the flag when desired.

15 The top brace 9 is of angle form in cross-section and is riveted to the side members 1 and face plate 5, and is connected at 16 to the crown member 11.

The crown member 11 is formed of sheet 20 metal from the blank shown in Figure 7 and is characterized by long reversely arranged slots 17 in its front and rear portions 18-19, respectively, and is also characterized by comparatively small slots 18^a arranged at 25 opposite sides of the mouths of the slots 17.

At 19^a are letters to form the name of the person buried, the said letters being carried by the portions 18 and 19 of the crown member 11 so that the name can be readily discerned by a party in front of or in the back of the marker. Each of the said letters 19^a is provided with an attaching portion 20 of T-form in cross-section, the said attaching portion being introduced slidably 30 into one of the slots 17 so as to strongly hold the letters to the portions 18 and 19. When it is necessary to resort to punctuation a member 19^b, bearing a punctuation mark 19^c and equipped with an attaching portion 20 is employed in either one of the 35 slots 17. Spacing members 21, Figure 15, are also used in the slots 17, the said spacing members being of H-form in cross-section as appears at the right of Figure 15. For 40 the closure of the slots 17, I employ closure plates 22, Figures 1, 16 and 17, each of the said closure plates being connected at 23 to the portion of the crown member 11 in which the slots 18^a are formed, and each 45 being provided with a protuberance 24, designed to rest in the mouth of the slot, and the nuts on the connecting bolts 23 being fixed in position by solder 25.

The data carrying frame before described 50 is numbered 30 and is formed of a blank such as shown in Figure 11. The said blank is shaped as illustrated, Figure 11, so as to form flanges 31 and 32, and the blank is provided with a plurality of horizontal slots 60 33 each of which terminates in one of the flanges 31 in an enlargement 34. The said enlargements 34 serve for the ready introduction of the attaching portions 35 of letters 65 36, the said attaching portions being of T-form in cross-section. In this connec-

tion it will be readily noticed that the flanges 31 and 32 as well as other flanges 36 and 37 on the plate or frame 30, bear against the face plate 5 and maintain the major portion of the frame or plate 30 in spaced relation 70 to the face plate, Figures 1 and 2. Manifestly when desired punctuation members 19^b such as shown in Figure 14 may be employed in the slots of the frame or plate 30, as may also spacing members 21, Figure 75 15. For the closure of the upper slot 33 in the frame 30, I provide the means shown in Figures 1, 18 and 19, said means comprising members 40 and 41, and a connecting bolt, set by solder 43, Figure 19.

Manifestly when deemed expedient such words as "Born", "Died", and "Age", may be each formed in a unit. This is clearly illustrated in Figure 21 in which the word "Born" is shown as a single piece.

It will be apparent from the foregoing that my novel grave marker is inexpensive in construction, is adapted to be shipped and stored compactly, and is capable in use of 90 withstanding the action of the weather. It 95 will also be apparent that when a particular grave is to be marked by one of my novel markers, the marker may be provided with the name and other data pertaining to the party buried, and this without the employment of skilled labor.

One of the main features of my novel marker is its adaptability to replace old grave boards, the scheme of my invention 100 contemplating the sale of the marker by mail or express; it being simply necessary for the party ordering to forward the necessary data, and to place the marker when received on the particular grave to be marked, no skilled labor being required for the latter operation.

In addition to the foregoing, it will be noted that the marker is neat in appearance, and that it is calculated to enable a party 110 searching to readily find any particular grave.

I have entered into a detailed description of the construction and relative arrangement of the parts embraced in the present and preferred embodiment of my invention 115 in order to impart a full, clear and exact understanding of the said embodiment. I do not desire, however, to be understood as confining myself to the specific construction and relative arrangement of parts inasmuch 120 as in the future practice of the invention various changes and modifications may be made such as fall within the scope of my invention as defined in my appended claims.

Having described my invention, what I 125 claim and desire to secure by Letters-Patent, is:—

1. A grave marker formed of sheet metal and comprising upright spaced side members of angle form in cross-section, an angle

- brace interposed between the side members and connected thereto at an intermediate point in the length thereof, a top brace also interposed between and connected to the side members, said top brace being provided with a staff-receiving aperture, a face plate connected to the side members, a plate connected with the face plate and spaced above the first-named brace and having an aperture coincident with the aperture in the top brace, a crown member connected to the top brace and having an aperture in coincidence with the said apertures, and an apertured spring strip arranged under and connected to the said plate, the several apertures being adapted to receive a flag staff, and the spring strip being adapted to engage said staff and prevent casual removal thereof. 25
2. A grave marker having an upper apertured portion, a lower apertured portion, 20 a rest under the latter, and an apertured spring strip carried by and disposed under said lower apertured portion and adapted to engage and prevent displacement of a flag staff. 25

In testimony whereof I affix my signature.

CECIL L. WILSON.
